UNITED STATES PATENT OFFICE.

JOHN C. TITUS, OF MARION, OHIO.

COMBINED CARBURETER AND GASOLENE-REGULATOR.

SPECIFICATION forming part of Letters Patent No. 693,462, dated February 18, 1902.

Application filed August 28, 1901. Serial No. 73,550. (No model.)

To all whom it may concern:

Be it known that I, JOHN C. TITUS, of Marion, Marion county, Ohio, (post-office address Marion, Ohio,) have invented certain new and useful Improvements in a Combined Carbureter and Gasolene-Regulator, of which the following is a specification.

This invention, relating to combined carbureters and gasolene-regulators especially applicable to gasolene-engines, will be readily understood from the following description, taken in connection with the accompanying drawings, in which—

Figure 1 is a vertical central section of my improved carbureter and gasolene-regulator; Fig. 2, a horizontal section of the same, and Fig. 3 a plan of the same with the needle-valve structure removed.

In the drawings, 1 indicates the body of the carbureter, illustrated as of hollow cylindrical form; 2, the outlet therefrom for the carbureted mixture, the same leading from the side of the body and being adapted for such connection as may be desired; 3, a cap-piece screwed firmly into the top of the body; 4, a large funnel-shaped air-opening vertically through the cap 3, the cap being provided with a downward extension, causing the lower extremity of this opening to be disposed well down within the body 1 at a point about level with the center of outlet 2; 5, a top plate in the cap 3 and forming a cover for the opening 4, this plate being pierced with register-openings; 6, a register-valve disposed concentrically upon the top plate 5 and adapted for angular adjustment thereon, so as to regulate the amount of air passing from the atmosphere through the air-opening 4; 7, the body of the gasolene-valve, the same being secured axially in top plate 5; 8, the gasolene-inlet to the gasolene-valve, the same being adapted to be piped to any suitable source of supply; 9, the needle-valve for the control of the flow of gasolene; 10, an overflow-nose secured centrally in the floor of the body of the carbureter axially in line with opening 4; 11, a nut upon this nose for clamping the same in position, the nose being provided with an enlarged head resting upon the floor of the carbureter; 12, a conical cavity formed in the upper surface of the head of nose 10, somewhat below the base of air-opening 4 and con-

centric therewith; 13, an outlet-pipe screwed upwardly in the axis of nose 10, its upper end projecting an adjusted distance into the cavity 12; 14, a stuffing-box on the lower end of nose 10 to pack around pipe 13 and permit of its being screwed up and down in the nose; 15, the lower end of pipe 13, adapted for connection to a suitable pipe to carry away surplus gasolene to a proper point of reception; 16, a rim extending upwardly from the head of nose 10, concentrically around the base of air-opening 4, the rear portion of this rim or that portion farthest from outlet 2 being much lower than that portion which is contiguous to the outlet, and 17 the discharge-nozzle of the gasolene-valve, the same extending downwardly through air-opening 4 and into cavity 12, its lower extremities being disposed to one side of the vertical plane of pipe 13.

Ignore pipe 13 for the present and assume that conical cavity 12 is closed at its bottom by any means. In such case if the gasolene-valve be opened and a quantity of gasolene be allowed to enter the cavity 12 and then a draft of air be drawn through the air-opening 4 and the outlet 2 the air entering the carbureter will impinge downwardly upon the gasolene in cavity 12 and will evaporate it and commingle with it, the mixture passing over rim 16 and out at outlet 2. If the rim 16 were of uniform height around the base of air-opening 4, the flow of air would be favored by outlet 2 and the attack of air upon the gasolene would be somewhat one-sided in the cavity, thus interfering with the perfection of the carbureting. By giving the front of rim 16 a superior elevation the favoring influence of the outlet on the air-current is neutralized and there is a fairly concentric attack of the air upon the gasolene and a fairly concentric flow of uniformly-carbureted air from cup 16 into the body of the carbureter.

It is found in practice that in using this carbureter in connection with gasolene-engines if the air-inflow to air-opening 4 is unrestricted at the time of starting the engine some difficulty arises, which difficulty is removed by temporarily throttling the air-inflow. This is done by partially closing register-valve 6 when starting the engine, the valve being later fully opened.

As thus far considered the bottom of gasolene-cavity 12 has been assumed as stopped up, so that the cavity formed a mere cup to hold the charge of gasolene. This would require very accurate and delicate adjustment of the gasolene-valve in order that the amount of gasolene delivered in the cup should be just right for each charge; but by the use of overflow-pipe 13 the charge of gasolene in cavity 12 is received around the upwardly-projecting end of pipe 13, the surplus overflowing through the pipe. By adjusting pipe 13 vertically the retained charge may be adjusted to a nicety, quite regardless of any delicate adjustment of the gasolene-valve. The sidewise deflection of the gasolene-nozzle 17 prevents the flow of gasolene directly downward into overflow-pipe 13.

I claim as my invention—

1. The combination, substantially as set forth, of a hollow carbureter-body having a horizontal outlet, a gasolene-cup disposed in the base of said body and having its rim disposed inwardly away from the wall of the body and having a rim portion at and as high as said outlet, a top to said body having a portion projecting down thereinto and concentrically within said gasolene-cup and having a funnel-shaped air-opening vertically through it, a gasolene-nozzle arranged to deliver into said gasolene-cup, and a valve to control the flow through said nozzle.

2. The combination, substantially as set forth, of a hollow carbureter-body having a horizontal outlet, a gasolene-cup disposed in the base of said body, a top to said body having a portion projecting down into the body and concentrically within said gasolene-cup and having a funnel-shaped air-opening vertically through it, a gasolene-nozzle arranged to deliver into said gasolene-cup, and a valve to control the flow through said nozzle, the rim of said gasolene-cup where it surrounds the base of said air-opening being higher at the portion toward the outlet from the carbureter-body.

3. The combination, substantially as set forth, of a hollow carbureter-body having a horizontal outlet, a gasolene-cup disposed in the base of said body and having its rim disposed inwardly away from the wall of the body and having a rim portion at and as high as said outlet, a top to said body having a portion projecting down thereinto and concentrically within said gasolene-cup and having a funnel-shaped air-opening vertically through it, a gasolene-nozzle arranged to deliver into said gasolene-cup, and a valve for controlling the flow of air through said funnel-shaped air-opening.

4. The combination, substantially as set forth, of a hollow carbureter-body having a horizontal outlet, a gasolene-cup disposed in the base of said body and having its rim disposed inwardly away from the wall of the body and having a rim portion at and as high

as said outlet, a top to said body having a portion projecting down thereinto and concentrically within said gasolene-cup and having a funnel-shaped air-opening vertically through it, a gasolene-nozzle arranged to deliver into said gasolene-cup, and a register-valve at the upper end of said funnel-shaped air-opening.

5. The combination, substantially as set forth, of a hollow carbureter-body having a horizontal outlet, a gasolene-cup disposed in the base of said body and having its rim disposed inwardly away from the wall of the body and having a rim portion at and as high as said outlet, a top to said body having a portion projecting down thereinto and concentrically within said gasolene-cup and having a funnel-shaped air-opening vertically through it, a gasolene-nozzle arranged to deliver into said gasolene-cup, and an overflow-pipe projecting upward from the floor of said gasolene-cup.

6. The combination, substantially as set forth, of a hollow carbureter-body having a horizontal outlet, a gasolene-cup disposed in the base of said body, a top to said body having a portion projecting down thereinto and concentrically within said gasolene-cup and having a funnel-shaped opening vertically through it, a gasolene-nozzle arranged to deliver into said gasolene-cup, and an overflow-pipe projecting upwardly from the floor of said gasolene-cup and vertically adjustable therein.

7. The combination, substantially as set forth, of a hollow carbureter-body having a side outlet, a gasolene-cup disposed therein and having a nose projecting through and secured to the floor thereof, an overflow-pipe screwed vertically upward in said nose and projecting into said gasolene-cup, a cap secured to said body and having a funnel-shaped air-opening projecting downwardly and concentrically into said gasolene-cup, a gasolene-valve disposed axially above said top piece, and a gasolene-nozzle connected with said valve and projecting downwardly through said air-opening into said gasolene-cup and deflecting to the side of said overflow-pipe.

8. The combination, substantially as set forth, of a hollow carbureter-body having a side outlet, a gasolene-cup disposed therein and having a nose projecting through and secured to the floor thereof, an overflow-pipe screwed vertically upward in said nose and projecting into said gasolene-cup, a cap secured to said body and having a funnel-shaped air-opening projecting downwardly and concentrically into said gasolene-cup, a gasolene-valve disposed axially above said top piece, a ported top piece in said cap at the top of said funnel-shaped air-opening, and a register-valve disposed over said top piece.
